UNITED STATES PATENT OFFICE.

WILLIAM R. CLARK, OF MUNCIE, INDIANA, ASSIGNOR TO CLARK CRANK COMPANY, OF INDIANAPOLIS, INDIANA, A CORPORATION OF INDIANA.

SAFETY ENGINE-STARTER.

1,098,480.

Specification of Letters Patent. Patented June 2, 1914.

Application filed May 13, 1912. Serial No. 696,861.

To all whom it may concern:

Be it known that I, WILLIAM R. CLARK, a citizen of the United States, residing at Muncie, in the county of Delaware and 5 State of Indiana, have invented a new and useful Safety Engine-STARTER, of which the following is a specification, reference being had to the accompanying drawings, and to the letters and figures of reference marked 10 thereon.

This invention relates to mechanical means designed to be actuated either by simple crank power or by means of a lever for starting explosion or internal combustion engines, the invention having reference 15 particularly to an engine starter of the above mentioned character that may be operated safely and without risk of being injured in case of back-firing or when the 20 engine starts in reverse to the proper direction.

An object of the invention is to provide explosion engines of automobiles with simplified and improved starting mechanism of 25 such construction as to be adapted to be actuated by the operator either when on his seat in the automobile, or when on the ground, as may be most convenient.

Another object is to provide cheaply constructed, reliable and durable starting apparatus, whereby danger to the operator due 30 to back-firing may be eliminated.

A still further object is to provide engine starting apparatus of such construction as 35 to be adapted to be applied to automobiles and their engines already in use.

With the above mentioned and other objects in view, the invention consists in improved engine starting mechanism comprising 40 a starting shaft provided with a crank and also lever actuated means for turning the shaft, and so constructed that either one of the actuating appliances may be omitted if desired; means for clutching or coupling 45 the starting shaft to the main shaft of the engine, and means for automatically disconnecting the starting shaft from the main shaft when the latter is rotated backward.

The invention consists also in the novel 50 parts and in the combinations and arrangements of parts as hereinafter particularly described and specified in the accompanying claims.

Referring to the drawings, Figure 1 is 55 a front elevation of an automobile frame and the improved engine starter; Fig. 2, a

transverse section of the starting shaft and rear elevation of apparatus thereon; Fig. 3, a fragmentary perspective view of one of the parts of the apparatus; Fig. 4, a fragmentary top plan of an automobile frame and explosion engine thereon, to which the improved starter is applied; Fig. 5, a section of the starting mechanism on the plane of the line A A in Fig. 1; Fig. 6, a plan 60 of one of the parts of the safety uncoupling apparatus; Fig. 7, a section of one of the parts of the housing of the coupling and uncoupling apparatus; Fig. 8, a fragmentary perspective view of the end of the main 65 shaft of the engine to which a part of the coupling apparatus is connected; Fig. 9, a central longitudinal section of the housing and journal-box of the starting shaft; Fig. 10, a fragmentary perspective view of one 70 of the parts of the starting mechanism; Fig. 11, a sectional elevation of the coupling and uncoupling apparatus and housing thereof; Fig. 12, a sectional view similar 75 to the preceding view omitting some of the parts of the mechanism, and Fig. 13, a fragmentary perspective view of the starting shaft and coupling and uncoupling device thereon.

Similar reference characters throughout 80 the drawings indicate corresponding elements or features of construction in the different figures thereof.

Well known parts of an automobile or 85 similar motor vehicle comprise frame bars 1 and 2, a front axle 3, a dash-board 4, an explosion engine 5, and a radiator 6, the explosion engine having a forwardly projecting main shaft 7.

In practically carrying out the objects of 90 the invention, a cylindrical coupling head 8 is provided and it is bored out and fitted onto the end portion of the main shaft 7 so as to project forwardly beyond the plane 95 of the end of the shaft and the head is secured to the shaft preferably by means of a rivet 9. The projecting portion of the wall of the head 8 has one or more recesses 100 therein, there being preferably two undercut recesses 10 and 10' extending inward 105 from the extremity of the wall, inclined guide faces 11 and 11' that extend at obtuse angles to the face of the extremity being formed at one side of the recesses to constitute uncoupling wedges, the entrance to 110 the recesses being relatively wide in order to provide clearance space for a clutch

device to readily enter the recess. The wall at the end of the under-cut side of the recess has short inclined faces 12 and 12' for thrusting off the clutch device when forced from the recesses. The rearward end of the head 8 preferably has a ball-race 13 therein to receive bearing-balls.

A journal box 14 of suitable length is provided and has supporting ears 15 and 15' thereon which are suitably bolted or otherwise secured to a suitable member of the automobile frame, such as a cross-bar 16. The journal box has a cylinder 17 connected to one end thereof by a continuous flange 18 or head portion 18 to constitute one part of a housing, the cylinder having a flange or ears 19 on its end portion. A collar shaped head 20 comprises a part of the housing and is bored out to receive the shaft 7, and may be placed on the shaft before the head 8 is secured thereto. The head 20 has a counterbore 21 of the required diameter to receive the head 8 and it has also a ball-race 22 at the bottom of the counterbore. Bearing-balls 23 are placed in the ball-races 13 and 22 but may in some cases be omitted or substituted by lubricating grease, and the rear end of the head 8 permitted to turn in contact with the bottom of the counterbore 21. The head 20 has a flange or ears 24 thereon corresponding to the flange or ears 19. The interior of the housing is provided with ratchet-teeth that collectively extend about the head 8, and this is preferably accomplished by providing an annular plate 25 on one side of which a series of ratchet-teeth 26, 26' are formed, the plate being placed over the head 8 with its opposite side against the forward side of the head 20, and the plate has bolt-holes 27 therein through which bolts 28 extend, the plate being placed against the end of the cylinder 17 and is fixedly secured to the cylinder and also to the head 20 by the bolts which extend through the flanges or ears 19 and 24.

A starting shaft 29 of suitable length is provided which is rotatably supported and is movable longitudinally in the journal box 14 in alinement with the main shaft 7, the journal box being supported in the required position, and when at rest the starting shaft is somewhat separated from the main shaft. The rearward end portion of the starting shaft 29 that is adjacent to the main shaft is provided with a transverse pivotal pin 30 which extends transversely beyond opposite sides of the shaft to constitute two studs on which two rollers 31 and 31' are mounted respectively, and also two push-bars similar to ratchet-pawl are mounted on opposite end portions respectively of the pivotal pin or studs. The push-bars extend obliquely toward the ratchet-teeth and are provided with springs 33 and 33' which are each secured to the

push-bar by a suitable securing device 34 to press the push-bars against the ratchet-teeth when the starting shaft is pushed toward the main shaft. The springs have integral tail extensions 35 and 35' that produce the desired spring tension when moved into contact with the ratchet-teeth, the extensions and the push-bars being carried away from the ratchet-teeth when the starting shaft is moved away from the main shaft to rest position. When the starting shaft is moved rearwardly substantially to the main shaft 7 and rotated in the direction of the arrow thereon the rollers enter the recesses 10 and 10' in order to clutch the starting shaft to the main shaft for starting the latter, and in this relative arrangement the push-bars are in contact with the ratchet-teeth 26 and slide over the teeth while the rollers are carried into the recesses. If now the starting shaft 29 is being turned in the required forward direction and the engine backfires and turns the main shaft in the reverse direction, the movement tends to also turn the starting shaft backward but the ends of the push-bars are stopped by engagement with the ratchet-teeth 26, and the push-bars being at an oblique angle to the plane of rotation of the pivotal pin 30 and the plane of the ends of the ratchet-teeth, the clutch members of the main shaft acting on the rollers 31 or clutch device of the starting shaft, force the push-bars to swing away from the coupling head so as to carry the rollers out of the recesses until they reach the inclined guides 12 and 12', which thrusts the starting shaft away in the clear so as to completely disconnect it from the main shaft. Preferably the rearward end of the journal box 14 has a recess 36 therein to receive a projection 37 on the starting shaft adjacently to the pivotal pin 30, to prevent the starting shaft from turning idly when not in use in case a starting crank is rigidly secured to the starting shaft, so as to maintain the crank in a convenient position.

A crank arm 38 is mounted to turn on the starting shaft 29 between a collar 39 and a ratchet wheel 40 which are secured to the shaft and prevent movement of the arm longitudinally of the shaft, the arm 38 having a pawl 41 therein to coöperate with the ratchet wheel for turning the shaft forwardly. It is obvious, however, that the arm 38 may be fixedly secured to the shaft if desired and it has a crank handle 42 thereon.

In order to hold the starting shaft away from the main shaft when the starting shaft is not in use, a spring 43 is coiled about the starting shaft and has an arm 44 on one end thereof that is seated against the forward side of the cross-bar 16 or against the journal box 14, the arm 44 preferably being

secured to the cross bar by a screw bolt 45. In case the starting shaft is to be actuated only by the hand crank the opposite end of the spring 43 is suitably connected with the 5 starting shaft 29 to enable the spring to yieldingly hold the shaft forwardly.

When it is desired to actuate the starting shaft by means of lever power an abutment 46 is suitably supported rigidly, and this 10 may be accomplished by means of a connecting arm 47 fixedly connected to the abutment and also to the cross-bar 16. A sleeve 48 is bored so as to receive the shaft 29 and permit either one to slide longitudinally 15 relative to the other and permitting the shaft to rotate in the sleeve, the sleeve being fitted into a suitable opening in the abutment so as to slide therein. The sleeve has an external longitudinal groove 49 therein 20 into which extends a spline 50 that is secured in the opening formed in the abutment to prevent rotation of the sleeve. The longitudinal movement of the sleeve rearwardly is limited by a suitable stop which preferably 25 consists of a collar 51 secured to the forward end of the sleeve against the abutment. The rearward end of the sleeve has a flange 52 thereon which carries a cylinder 53 having a smooth end 54 constituting a 30 guide. A recess 55 is formed in the wall of the cylinder and extends from the guide end 54 and has inclined sides 56 and 57 constituting cams. A coil spring 58 extends about the sleeve 48 and is seated against the 35 abutment and also against the flange 52 for yieldingly holding the cams in normal position. A collar 59 is secured to the shaft adjacent to the rearward end of the sleeve. A pulley 60 has a hub 61 which is rotatably 40 mounted on the shaft 29 at the rearward side of the collar, and a ratchet-wheel 62 is secured to the shaft at the rearward side of the hub. A pawl 63 is mounted on the pulley to coöperate with the ratchet-wheel for 45 turning the shaft in forward direction. The forward side of the pulley has a cylindrical buffer 64 thereon adapted to seat against the end 54 of the cylindrical head 53 and it has a projecting V-shaped cam 65 thereon 50 adapted to fit into the recess 55, the recess receiving the cam when the shaft 29 is moved to its forward position and forces the shaft rearward so as to clutch with the main shaft when the pulley is rotated. The spring 43 55 has an arm 66 on its forward end that is provided with a hook 67 which is inserted through a hole 68 and hooked to the pulley 60, for retracting or rotating the pulley backward after it has been rotated in forward direction to rotate the starting shaft. The spring 43 as will be seen in this case 60 performs two functions and is somewhat weaker than the spring 58. A cable 69 is wound one or more times about the pulley 65 60 and secured thereto and leads away from

the undermost portion of the pulley, and it is connected to a suitable lever 70 mounted on the automobile frame rearward of the plane of the dash-board 4, the cable being guided by a suitable number of sheaves 71 70 and 72 suitably mounted on the frame. The lever may be variously designed in detail and arranged as may be most convenient.

In order to lessen the cost, in some cases 75 the lever actuated mechanism may be omitted if desired, the starting shaft being actuated by means of the hand crank.

In practical use force may be applied to the crank arm 38 while the shaft 29 is pushed rearward so as to become clutched to the main shaft, the main shaft being partially rotated as is required until explosions occur in the engine, the shaft 29 turning freely in the sleeve 48 and in the hub of the pulley. When the clutched starting shaft 80 is rotating forwardly if turned by the pulley the cam 65 is guided against the end 54 of the head 53, and if now the engine starts backward and causes the push bars to force the starting shaft forward, the cams 85 90 and also the sleeve 48 are forced forward, and the spring 58 is slightly compressed and again forces the sleeve rearward when the pulley is retracted to rest position, when the cam 65 again enters the recess 55. When 95 the pulley is started forward by means of the cable 69 the cam 65 is forced out of the recess and guided against the guiding end 54 until one revolution of the pulley takes place. It may be designed that the pulley 100 shall turn farther than one complete revolution and in this case the movement is rapid and the cam 65 is carried past the recess without entering, the pressure of the spring 43 being relatively slight. When the starting shaft is actuated by the hand crank the cam 65 simply moves out of the recess 55 and back again without being carried about the shaft, it being understood that the cable is of suitable length to limit the backward 105 rotation of the pulley. Other results of the operation of the mechanism will be fully understood in connection with the description of the construction and function of various parts thereof.

Having thus described the invention, what is claimed as new is:

1. A safety engine-starter including a rotatable main shaft provided on its end with an annular projection having an undercut 120 recess in its end face, one side of the recess being inclined relative to the face, a fixedly supported collar extending about the main shaft and having ratchet-teeth on its face, and a starting shaft rotatably supported to 125 move toward or from the main shaft and having a stud thereon that is carried into or out of the recess, the stud having a push-bar thereon that is spring-pressed toward the ratchet-teeth, the push-bar being in contact 130

- with the ratchet-teeth when the stud is carried into the recess to rotate the main shaft by means of the starting shaft in one direction, the main shaft on rotation in the 5 opposite direction causing the push-bar to stop against one of the ratchet-teeth and force the stud out of the recess.
2. A safety engine-starter including a rotatable main shaft having a clutch member thereon, a rotatable and longitudinally movable starting shaft in alinement with and adjacent to the main shaft and having a clutch device thereon for coöperation with the clutch member to rotate 10 the main shaft in forward direction, a support for the starting shaft, a fixed abutment, a sleeve on the starting shaft and slidingly supported in the abutment and having a cam thereon, a stop for limiting 15 the movement of the sleeve toward the clutch device, a spring seated against the sleeve and the abutment yieldingly forcing the sleeve toward the clutch device, a ratchet-wheel and a collar secured to the starting shaft, a 20 pulley rotatable on the starting shaft between the ratchet-wheel and the collar and having a cam thereon to coöperate with the cam of the sleeve, a pawl mounted on the pulley to coöperate with the ratchet-wheel 25 for rotating the starting shaft in forward direction, a cable connected to the pulley for turning it in forward direction, and a spring coiled on the starting shaft and connected to the pulley and also to the starting 30 shaft support, the spring being tensioned for retracting the pulley and also for forcing the clutch device away from the clutch member, the cams acting on forward movement 35 of the pulley to force the clutch device into 40 contact with the clutch member.
3. In an engine starter, the combination with a rotatable main shaft, of an annular head secured to and projecting beyond the shaft, the end of the head having a recess 45 therein, a fixedly supported housing adjacent to the head and having a series of teeth fixed therein that collectively extend about the head, a starting shaft rotatably supported to move longitudinally to or from the head 50 and having a pivotal pin thereon, a roller and also a push-bar mounted on the pin, the roller being movable into or out of said recess, the push-bar extending obliquely toward the plane of the series of teeth, and a 55 spring secured to the push-bar and having a tail extension to be carried to the teeth for forcing the push-bar to the teeth.
4. In an engine-starter, the combination with a fixed journal box and a fixed abutment, and a rotatable main shaft having a 60 clutch member, of a sleeve slidingly and non-rotatably mounted in the abutment and yieldingly spring-pressed toward the jour-
- nal box, a stop for limiting the movement of the sleeve toward the box, a starting shaft 65 rotatably mounted in the journal box and the sleeve and having a clutch device thereon to coöperate with the clutch member, the starting shaft being movable in the sleeve and the box toward or from the main shaft, 70 a pulley rotatable on the starting shaft, means between the sleeve and the pulley for moving the starting shaft to the main shaft, means for clutching the pulley to the starting shaft, a cable connected to the pulley, and 75 a spring for retracting the pulley.
5. In an engine-starter, the combination with a rotatable main shaft, a fixed journal box, and a fixed abutment, of a sleeve mounted to move longitudinally in the abutment 80 toward or from the main shaft and having a flange on one end, a cylinder supported on the flange and having a V-shaped recess in its end, a spring on the sleeve seated against one side of the abutment and the flange, a 85 stop device fixed on the opposite end of the sleeve and normally in contact with the opposite side of the abutment, a starting shaft rotatably mounted in the journal box and the sleeve and movable longitudinally therein, coöperating clutching means on the main shaft and the starting shaft enabling the latter to rotate the former, a ratchet-wheel and a collar secured to the starting shaft, a pulley rotatably mounted on the starting shaft 90 between the ratchet-wheel and the collar, a pawl carried by the pulley to coöperate with the ratchet-wheel, a cam carried by the pulley to be guided on the end of the cylinder or into or out of the recess, a spring coiled 95 about the starting shaft and having an arm secured to the journal box and also an arm connected to the pulley, and a crank arm on the starting shaft.
6. In an engine-starter, the combination 105 with a rotatable main shaft, a head on the shaft having a recess therein, and a fixed collar extending about the shaft and having a series of teeth thereon, of a rotatable starting shaft in alinement with and movable toward or from the main shaft, a pivotal pin mounted transversely in the starting shaft, a roller and also a push-bar carried by the pin, the roller being movable into the recess 110 for rotating the main shaft in one direction, the push-bar extending obliquely toward the plane of the series of teeth, and a spring 115 connected with and holding the push-bar in contact with the teeth only when the roller is in the recess.
